UNITED STATES PATENT OFFICE.

FRANK G. STIMSON, OF HAMDEN, CONNECTICUT, ASSIGNOR TO WINCHESTER REPEATING ARMS COMPANY, OF NEW HAVEN, CONNECTICUT, A CORPORATION OF CONNECTICUT.

ANTIROLLING HANDLAMP.

Application filed May 20, 1922. Serial No. 562,319.

To all whom it may concern:

Be it known that I, FRANK G. STIMSON, a citizen of the United States, residing at No. 1148 Whitney Avenue, Hamden, in the 5 county of New Haven, State of Connecticut, have invented certain new and useful Improvements in Antirolling Handlamps; and I do hereby declare the following to be 10 a full, clear, and exact description of the invention, such as will enable others skilled in the art to which it appertains, to make and use the same.

The present invention relates to battery hand lamps of the type wherein an electric 15 battery operates in conjunction with a small incandescent lamp bulb and a reflector to project a beam of light through a lens.

It is an object of the present invention to 20 provide a tubular hand lamp with a head of such cross section that the hand lamp will not readily roll when laid down on a sloping surface.

In the preferred embodiment illustrated 25 in the drawing, the flaring, sheet metal head is of polygonal cross section, but with a cylindrical front edge to which the usual lens supporting ring may be threaded.

Further objects and advantages will become clear from the following detailed 30 description, taken in conjunction with the accompanying drawings, wherein,

Fig. 1 is a side elevation of the complete hand lamp;

Fig. 2 is an end elevation of the same.

35 Fig. 3 is a section of the flaring head on the line 3—3 of Fig. 2 and Fig. 4 is a similar section on the line 4—4.

Fig. 5 shows the invention applied to a 40 tubular hand lamp in which the battery casing consists for the most part of a fiber tube.

Referring to Figs. 1 to 4 inclusive, the metal casing 1 wherein the batteries are housed is provided with the usual bottom cap 2 threaded thereto, and a sliding thumb 45 piece 3, it is threaded at its front end to engage with the threaded cylindrical portion 4 of an outwardly flaring sheet metal head 5.

This head has at its front edge a cylindrical portion 6 (Fig. 3), with threads pressed 50 therein, for engagement with the threads 7 of a ring or collar 8 of usual construction, whereby a lens 9 is supported. The lens shown in the drawing has a plane front face.

The sheet metal head 5 is pressed or

shaped by usual metal working operations 55 to form a plurality of facets 10, eight in number, and each presenting a substantially plane surface of about the outline indicated in Figs. 3 and 4. This gives to the periphery of the flaring head an octagonal outline, 60 as indicated in Fig. 2, with the corners of the octagon projecting far enough to serve as anti-rolling shoulders when the hand lamp is laid down on a flat surface, as indicated diagrammatically in Fig. 1. 65

Such a hand lamp is ornamental in appearance, is light in weight, has its weight well distributed, is economical to manufacture and offers no impediment to the ready attachment of the lens supporting ring or 70 collar.

In the embodiment illustrated in Fig. 5, the tubular casing 11 is of fiber with threaded collars 12 and 13 riveted thereto. Collar 12 is threaded to receive a bottom cap 14 and collar 13 is threaded to receive the cylindrical portion of the flaring sheet metal head 15. The latter may be the same in details of construction as the head shown in Figs. 3 and 4 and is threaded at its front edge to 80 receive the knurled collar 16 whereby the convex lens 17 is supported in front of the usual reflector and lamp bulb. Various changes in details of construction and in the form of the flaring head may be made 85 without departing from the spirit of my invention as defined by the appended claims.

I claim:—

1. A tubular hand lamp having a flaring sheet metal head with projecting shoulders and a threaded cylindrical front portion, and a lens-supporting collar threaded to said cylindrical portion, the diameter of said collar being such that said shoulders may impede the rolling of said hand lamp when laid on 95 a plane surface.

2. In a battery hand lamp, the combination of a cylindrical casing having a threaded front end, a flaring sheet metal head threaded thereto, said head being shaped with facets to form a polygonal periphery, and having a cylindrical front edge threaded to receive a lens-supporting ring, said ring being of such diameter that the polygonal portion of the head can serve as an anti- 105 rolling device.

In testimony whereof I affix my signature,
FRANK G. STIMSON,
